(57) **CLAIM**

The ornamental design for a light fixture as shown and described.

DESCRIPTION

FIG. 1 is a front perspective view of a light fixture showing our new design; and,

FIG. 2 is a front perspective view of the light fixture of FIG. 1 shown in an illuminated state.

The light fixture is shown with a symbolic break in its width. The appearance of any portion of the light fixture between the respective adjacent break lines forms no part of the claimed design. The radiating lines emanating from the design in FIG. 2 schematically represents illumination. The broken lines depicting the remainder of the light fixture form no part of the claimed design.
